UNITED STATES PATENT OFFICE.

WILLIAM F. LUICK AND ALVIN J. BASSETT, OF MILWAUKEE, WISCONSIN, ASSIGNEES
TO LUICK BASSETT PRODUCER COMPANY, A CORPORATION OF WISCONSIN.

GAS-PRODUCER.

1,062,721.

Specification of Letters Patent. Patented May 27, 1913.

Application filed October 3, 1911. Serial No. 452,362.

To all whom it may concern:

Be it known that we, WILLIAM F. LUICK and ALVIN J. BASSETT, both citizens of the United States and residents of Milwaukee, in the county of Milwaukee and State of Wisconsin, have invented certain new and useful Improvements in Gas-Producers; and we do hereby declare that the following is a full, clear, and exact description thereof.

10 The object of our invention is to provide a simple, effective and economical gas producer.

With the above object in view the invention consists in certain peculiarities of construction and combination of parts as hereinafter set forth with reference to the accompanying drawings and subsequently claimed.

The drawing illustrates a sectional elevation of a complete gas producing plant embodying the features of our invention with parts broken away and parts in section to better show certain structural features.

25 Referring by characters to the drawing 1 represents a metallic jacket of a gas producer generator, 2 the head thereof and 3 the ash pit, over which is suspended from the jacket walls, a fuel grate 4, the said jacket walls being provided with the usual fuel and cleanout openings 5, 6, respectively, and their closures. A circular fuel pot 7 is supported with the jacket by brackets 8 that extend inwardly therefrom, the walls of the

30 fuel pot being constructed of suitable inner and outer layers of fire brick 7', 7'', respectively. The outer layer 7'' is reinforced by a metal shell 9 which shell is formed with an outward flared offset 9' in approximate alignment with the upper edge of the firepot, and terminates with a vertically disposed flange that is secured to the jacket directly under its head 2. The shell 9 in conjunction with the jacket forms an annular 35 air chamber 9'' about the fuel pot that is closed at its top edge and open at its bottom, whereby a free circulation of air therefrom is admitted to the ash pit, and by draft caused to travel up through the fuel pot.

40 The air chamber 9'' is interrupted by a pair of perforated horizontally disposed rings 10, 10', the ring 10' of which pair partially closes the lower open edge of the chamber and constitutes a discharge mouth, it being understood that the combined area

of the apertures of each ring is approximately sufficient to provide the required volume of air and that said rings serve as baffles to break up the air current, whereby it is evenly discharged about the lower edge 60 of the fuel pot walls. Air is supplied to the chamber 9'' through a pipe 11 that communicates with the upper portion of said chamber, the air supply from the pipe being controlled by a valve 11' preferably of 65 the quick opening type.

The outer fire-brick layer 7'' of the fuel-pot terminates below the mouth of said fuel pot and in conjunction with the shell 9 forms an inclosure constituting an annular 70 gas pocket 12 that is located between the inner layer of fire-brick 7'' and the upper portion of said shell 9. A communication between the gas pocket 12 and a gas delivery fine 13 is formed through the interposition 75 of a thimble 12' that is fitted to corresponding apertures in the walls of the shell 9 and generator jacket, the gas delivery flue being in turn connected to the head of a heating drum 14. A T section 13' of the flue has 80 one branch that communicates with the drum bottom and another branch 13'' that is connected to a bonnet 14', the third branch constituting a catch-basin that is provided with a cleanout cap 15, whereby access may 85 be had thereto. The bonnet 14' is mounted in an open mouthed trap 16 with which it communicates by means of end ports 17, the lower end of the bonnet being sealed by a column of water. This water column is 90 maintained at predetermined normal height under control of a waste pipe 18 having a valve 18', the waste pipe being provided with an overflow branch pipe 18'' which communicates with the trap at a higher level 95 than the valve-controlled main waste pipe and bridges its valve. Water is supplied to the trap 16 from a drain-pipe 19 that communicates with said trap and the bottom 20' of a cylinder 20 that contains suitable filters and comprises a scouring apparatus.

The crown 14' of the bonnet is provided with a depending vent-pipe 21, the mouth of which terminates slightly above the normal height of the trap water seal, the vent 105 pipe, in turn, being connected to a stack 21' for carrying off the gases incidental to an initial firing of the gas generator. The bonnet 14' is also provided with a gas delivery flue 12'' that conducts the supply of 110

gas from the generator to the scrubbing cylinder 20, the said flue being arranged to discharge under a grating 22 that serves as a support for a wet scouring body of filter material 23, which material is preferably stone. The upper portion of the cylinder 20 of the scouring apparatus is provided with a second grating 22' between which and the adjacent head of said cylinder is a second body of dry filter material such as coal, through which the gas product passes and is delivered to the point of storage or consumption through a supply-pipe 24, the cylinder head being provided with a suitable hand-hole whereby access may be had to scouring substance.

As a protection from intense heat generated within the open mouth of the fuel-pot 7 we provide the head 2 of the jacket 20 with a water jacket 25, which is preferably in the form of a flat ring disposed about a feed aperture 26 of said generator head 2, the water jacket being interrupted at spaced distances by suitable thimbles 27 that constitute poke holes having adjustable covers 27'. The inner face of the water jacket 25 is arranged, with respect to its distance from the top edge of the fuel-pot inner lining 7', so as to form a gas passage that is approximately equal to the circumferential area of the fuel-pot and by such arrangement it will be readily understood that the gas is forced to escape from said fuel pot over its edge in an even radially disposed thin sheet to the pocket 12, and by this even discharge of gas and the even feed of air from below as previously described it is apparent that the combustible fuel will not be affected by streaks of uneven temperature passing therethrough resulting in the production of clinkers.

A fuel magazine 28 is fitted to the head 2 of the gas generator jacket about its aperture, the same being provided with a cap closure and bottom that is controlled by gravity closing valve 28' as shown, whereby fuel charges are supplied to the pot below. The heating drum 14 carries a steam generating pipe 29 that is preferably flat in cross-section and coiled in a zig-zag manner throughout the length of the drum, the last leg of the coil being in communication with the gas generator air chamber 9' just above its ring 10' through the medium of an interposed coupling pipe 29' that is provided with a branch 29'' which communicates with the ash-pit 3, the same constituting a drain for condensation.

As shown in the drawing, the hot gases, in passing through the drum travel over the side edges and through the spaces between the loops of steam generating pipe whereby the same is heated to the desired temperature to produce steam by the evaporation of a small quantity of water that is continu-

ously supplied in a thin jet to the upper leg of the pipe, the steam so generated being thoroughly superheated as it travels through the coil and is discharged into the air chamber 9'' in a dry state.

An important feature of our invention, in connection with the other features of the steam generator just described is the arrangement of water supply thereto. The water distribution system comprises a feed-pipe 30 which delivers water under pressure to the gas generator water jacket 25, where it serves as a cooling medium, and from said water jacket a lead pipe 30' is connected to a spray head 31 that is located within the scouring apparatus whereby water is admitted to the scouring material 23. This lead pipe has a branch 30'' fitted with a pin-valve 32, the nozzle of which is incased in a sight-feed housing 33 and adapted to discharge into the mouth of a pipe section 30''', the mouth of the same being also incased within the housing. The lower end of the pipe section is coupled to the top leg of the steam generator pipe 29 as shown, and by the above fitting it will be seen that said steam generator is entirely closed from the atmosphere except at its lower point of discharge, the back pressure of the generated steam upon the small jet of water being practically unappreciable. Hence by proper manipulation of the pin-valve water delivered from the closed system can be instantly converted into a highly expansible dry steam for immediate consumption, resulting in great efficiency in the production of a commercial water gas.

In the initial operation of our gas generating apparatus the fresh fire in the fuel pot is supplied by air only through the valve-controlled pipe 11, the pin-valve 32 which supplies water to the steam generator being closed. The initial gases therefore will pass from the gas pocket 12, through the flues and bonnet 14' and from thence to atmosphere through the vent-pipe 21 to the stack 21'. After the fuel has reached the desired temperature, valve 18 in the drain pipe 18' is closed, whereby the water from the scouring apparatus will rise within the trap and thus cut off communication of the gases, with the atmosphere through vent-pipe 21, which pipe is thus sealed. The water seal thereafter will be maintained at the level of the overflow branch-pipe 18'' of the drain. The pin-valve 13 of the water-supply system is now opened to permit a jet of water to flow into the steam generator coiled pipe 29. The said pipe being previously heated by the gases passing therethrough, will instantly generate steam which is discharged into the air-chamber 9'' and after commingling with the air therein said moist air will be drawn into the fire pot and up through the body of fuel, whereby

moisture and oxygen are added in the proper proportions to produce an efficient gas. This gas passes over the mouth of the fire pot into the gas pocket 12 in equal and even 5 quantities throughout the full circular area of said fuel pot and thereafter the gas travels through the flue 13 and the heating drum 14 to the scouring apparatus, in a direct line through the hood 14' to the lower 10 end of said scouring apparatus. The gases thereafter pass up through said scouring apparatus and are delivered to the source of consumption or storage in the usual manner, it being understood that the pipe 24

15 of the scrubbing cylinder is under suitable valve control not shown, whereby the gas during an initial operation is prevented from passing therethrough.

Particular attention is called to the steam 20 generating and air mixing apparatus operating in conjunction with an unobstructed open mouth fuel pot, which is rendered practical, owing to the fact that the generator head is provided with a water cooled 25 jacket, another essential feature of the invention being the arrangement whereby a valve, in the form of a water-seal, is utilized for controlling the gases, the elasticity of 30 which valve renders it possible to avoid accidents due to explosion of the gases in which case the water seal will readily yield to the force.

Another important feature of our invention 35 in connection with the air and steam supply to the generator, is that by said arrangement, the ash-pit cleanout doors can be opened without interfering with the uniform operation of the apparatus. When it is desirable to clean out the ash-pit, the air 40 supply pipe valve is closed and the draft of air admitted through the open door will be met by the steam supply from the chamber in a circular sheet, and the steam laden air will thus be drawn up through the bed of

coals in a similar manner to that previously 45 described in connection with the supply from pipe 11, there being no appreciable difference in the operation, whether the air supply is delivered through the feed pipe 11 or ash-door opening, it being understood 50 that the temperature of the steam in the chamber will cause the rush of air through said door to be initially drawn toward the discharge mouth of said chamber where it meets the sheet of steam that is discharged 55 therefrom.

We claim:

In a gas producer having a jacket, a head closure therefor, an offset shell secured to the jacket adjacent to its head to form a gas 60 pocket, the shell being extended parallel with the jacket and having an open lower end forming in conjunction with said jacket an air chamber, an air supply pipe in communication with the upper end of the air 65 chamber, and a gas discharge pipe in communication with the gas pocket; the combination of a perforated baffle-ring interposed between the jacket and shell below the air supply pipe, a second perforated baffle- 70 ring interposed between the jacket and shell at the lower end of said shell, layers of refractory material fitted within the shell to form a fire-pot, and a steam supply pipe having a branch in communication with the 75 air chamber above the lower baffle-ring and a second branch pipe in communication with the fire-pot below said baffle-ring.

In testimony that we claim the foregoing we have hereunto set our hands at Mil- 80waukee in the county of Milwaukee and State of Wisconsin in the presence of two witnesses.
